UNITED STATES PATENT OFFICE.

FRANK E. LANGDON, OF VANCOUVER, WASHINGTON.

WINDING SHAFT.

Application filed April 28, 1926. Serial No. 105,104.

This invention relates generally to the paper making industry, and particularly to devices for rewinding paper from large rolls which are made by the paper making machines into smaller marketable rolls cut to the desired width and rolled to a given diameter.

The main object of this invention is to construct an exceedingly simple and efficient winding shaft which remains expanded while paper is being wound thereon and can be contracted to permit the easy removal of the rolls from the shaft.

These, and other objects, will become more apparent from the specification following as illustrated in the accompanying drawing, in which:

Figure 1 is a longitudinal section through the shaft showing a roll of paper wound on same and having its mid-section broken away for the purpose of shortening the drawing without reducing the scale. Figure 2 is a view similar to Figure 1 but showing the shaft contracted without the paper. Figure 3 is a fragmentary side elevation of the interior portion of the shaft showing the expanding means and the slot for the shifting lever. Figure 4 is a transverse section taken along the line 4—4 in Figure 1. Figure 5 is an end elevation of the shaft taken along the line 5—5 in Figure 1.

Figure 6 is a section taken along the lines 6—6 of Fig. 3.

Similar numbers of reference refer to the same parts throughout the several views.

Referring in detail to the drawing, the device is composed of the following parts, a tubular inner shaft 10 provided at one end with a plug end 11 having a small shaft 12 formed thereon, as well as a shank 13 which fits snugly into the shaft tube 10 and is secured thereto by means of a pin 15 which projects out of each side of the tube 10. A slot 16 is formed in the tube 10 to receive a pry bar and a small slot is formed in the shank 13, for the same purpose.

The opposite end of the tube 10 is provided with a threaded plug 17 having a hexagonal portion 18 and a small shaft end 19 corresponding with the end 12.

Around the tube 10 near the plug 17 is placed a sleeve 20 having an undercut end 21. The sleeve 20 is secured to the tube 10 by means of the screw 22.

Outside of the tube 10 are placed three

portions 23 of the outer shaft adapted to be expanded radially so that when expanded they form a cylindrical shaft. Each member 23 is tapered at one end to slip under the end 21 of the sleeve 20. The opposite end of each member 23 is grooved to receive the end 24 of a slid able sleeve 25 whose slot 26 is somewhat shorter than the slot 16 in the members 10 and 13. The ends of the pin 15 occupy the portion of the space in the slots 26 in the sleeve 25.

Each member 23 is provided on its inner face with a plurality of expander blocks 27 which are secured to their member by the shouldered rivets 28 whose bodies 29 can slide in the slots 30 in the member 10 and whose heads 31 on the inside of the member 10 prevent the bulging of the members 23.

It is preferable to enlarge a portion of each slot 30 to admit the heads 31, as illustrated. In some instances it may be desirable to omit the heads on the outermost rivets to facilitate the assembling of the parts, and to depend upon the sleeves 20 and 25 to prevent undue expansion of the ends of the members 23.

The expander blocks 27 have one rounded end 32 and one rounded side 33 which engages the side of the member 23. The side 34 is flat and rests against either the bottom 35 of the groove 36 in the contracted position or on the bench 37 in its expanded position.

Inside of the tube 10 is placed a disk 38 which is held in position by the studs 39. A similar disk 40 is placed against one side of three rivet heads 31. The disks 38 and 40 are provided with eye bolts 41 on each of which is placed a nut 42. A spring 43 is placed in tension between the eye bolts 41.

The operation of the device is as follows: Paper from the paper machine is slit and rolled on to the above described winding shaft. When it is desired to withdraw the winding shaft from the rewound rolls of paper the operator merely inserts a bar into the slot 16 and pries the tube 10 longitudinally with relation to the members 23, which permits the expander blocks 27 to drop into the grooves 36 permitting the member 23 to contract and the shaft to be easily withdrawn from the new rolls of paper.

When the shaft is free of the rolls the bar is withdrawn from the slot 16 and the spring 43 now returns the members 23 to their expanded position.

Naturally the mechanical details of this device may be varied greatly without departing from the spirit of this invention.

I claim:

5. 1. A winding shaft having an inner tubular shaft member; a plurality of radially movable longitudinal curved sections forming an outer shaft around said inner shaft; wedges between each of said longitudinal sections and said inner shaft; means for sliding said inner shaft with relation to said outer sections; and a spring within said inner tubular shaft adapted to hold said sections in an expanded position.
10. 2. A winding shaft consisting of a tubular central shaft having a plug end shaft at each end thereof; a plurality of curved sections around said tubular member uniting to form an outer expansible shaft; a sleeve

fixed on one end of said tubular inner shaft 20 adapted to confine said sections against over-expansion; a slideable sleeve on the opposite end of said tube adapted to slide all of said sections along said inner shaft, said sleeve and said tube having slots formed 25 therein adapted to receive a prying lever; a plurality of wedging expander blocks between said sections and said tube, each of said blocks having a corresponding recess formed in the tube serving as a cavity for 30 receiving said block in a contracted position and having a sloping end thereon whereby said block can slide into an expanded position; and spring means between said outer sections and said inner shaft adapted to slide 35 said inner shaft in a manner to force said sections into an expanded position.

FRANK E. LANGDON.
